UNITED STATES PATENT OFFICE.

FRANCIS L. CLARK, OF PITTSBURG, PENNSYLVANIA, ASSIGNOR TO THE
WESTINGHOUSE AIR BRAKE COMPANY, OF SAME PLACE.

HYDRAULIC BRAKE.

SPECIFICATION forming part of Letters Patent No. 656,517, dated August 21, 1900.

Application filed June 7, 1899. Serial No. 719,667. (No model.)

To all whom it may concern:

Be it known that I, FRANCIS L. CLARK, of Pittsburgh, in the county of Allegheny and State of Pennsylvania, have invented a certain new and useful Improvement in Hydraulic Brakes, of which improvement the following is a specification.

My present invention relates to and is an improvement in hydraulic brake apparatus of the general character of that set forth in Letters Patent of the United States Nos. 574,663 and 574,665, granted and issued to me under date of January 5, 1897, and No. 615,141, to the Clark Brake Company, as my assignee, under date of November 29, 1898. Said Letters Patent exemplify means for preliminarily taking up the slack of the connections and the clearances between the brake-shoes and the wheels and subsequently applying the brakes by the action of separate and independent brake-cylinder pistons; and the object of my present invention is to provide a more effective and desirable controlling-valve mechanism for application in a brake system in the operation of which the above-stated functions are performed.

The improvement claimed is hereinafter fully set forth.

In the accompanying drawings, Figure 1 is a vertical longitudinal central section through a brake-cylinder and controlling-valve mechanism embodying my invention; and Figs. 2, 3, and 4, similar sections, on an enlarged scale, through the controlling-valve mechanism detached, showing the movable members in different positions assumed by them in operation.

In the practice of my invention I provide two brake-cylinders 6^a of larger and smaller diameters, respectively, which are connected in line axially through an interposed head 6^b and are provided with pistons 56 51^b, acting through their piston-rods upon a system of brake-levers, substantially as in the construction shown in Fig. 3 of Patent No. 615,141, aforesaid. The brake-cylinders differ, however, from those shown in said figure in the particulars that a flexible diaphragm 51, working between the cylinder-head 6^b and a perforated stop-plate 53, is employed in lieu of the piston 51 of said figure. The piston-rod

sleeves work through stuffing-boxes in the cylinder-heads, and release-pipes, controlled by a cock, are provided for drawing off liquid as desired from the cylinder-spaces in which the pistons 56 and 51^b and the diaphragm 51 operate. In these particulars the construction herein set forth accords substantially with that set forth in Letters Patent of the United States No. 641,625, granted and issued to me under date of January 16, 1900, and they are not in and of themselves claimed as of my present invention.

As in Patent No. 615,141 aforesaid, a rod 14, which abuts against the piston 51^b of the smaller brake-cylinder 6^a, is coupled by a pin 14^a to one end of a brake-lever 17, the opposite end of which is connected by a brake-rod 25 to the brake-beam (not shown) of one pair of wheels of the car. A rod 16, which abuts against the piston 56 of the larger brake-cylinder 6, is coupled by a pin 16^a to one end of a brake-lever 17^a, the opposite end of which is connected by a brake-rod 25 to the brake-beam of another pair of wheels of the car. The brake-levers 17 17^a are intermediately connected by a brake-rod 18.

The supply and discharge of liquid to and from the brake-cylinders 6 6^a in the application and release, respectively, of the brakes are effected by a valvular mechanism inclosed in a casing 40, which communicates by a pipe 5^f, leading to a port in its peripheral wall, with a pipe which extends to a pump or other source of liquid under pressure and which also serves for the discharge of liquid on the cessation of operation of the pump or the release of pressure within it. A pipe 5^h connects another port 49^b in the valve-casing with the larger brake-cylinder 6, between the head 6^b thereof and the diaphragm 51. Direct communication between the pipe 5^h and the pipe 5^f is controlled by a release check-valve 52, which opens upwardly or toward the pipe 5^f. A pipe 5^g leads from another side port in the valve-casing 40 to the smaller brake-cylinder 6^a. The traverse of liquid from the pipe 5^f to the pipes 5^g and 5^h is controlled, as presently to be described, by two lift or poppet valves 47 47^a, a piston 49, and a diaphragm 50, all of which are fitted to work in the valve-casing 40, and the release or return

of liquid from the pipes 5^g and 5^h to the pipe 5^f is controlled by said valves, piston, and diaphragm, and by the release check-valve 52. The piston 49, which is secured to and moves with the diaphragm 50, is provided with a central bore or passage 49^a, the lower end of which communicates continuously with the port 49^b, which is open to the pipe 5^h. The valve 47^a is secured upon a stem 48 and is adapted to seat around and close the upper end of the central bore 49^a of the piston 49. The valve 47 is of greater diameter than the valve 47^a, and the diaphragm 50 is of greater diameter than the piston 49. The valve 47 is normally held by a spring 51^c off a seat formed around the upper end of a passage 47^b in a wall or partition in the casing which separates the side ports therein to which the pipes 5^f and 5^g are respectively connected, and the valve 47 is connected to the stem 48 of the valve 47^a, so as to be movable coincidently with the latter. A spring 51^c in an extension 40^a of the valve-casing bears against the lower side of the diaphragm 50, and the tension of said spring may be varied as desired by an adjusting-screw 51^a.

Fig. 1 shows the parts in running position—that is to say, when the brakes are fully released and when liquid under pressure may be admitted to the brake-cylinders to effect an application of the brakes. The brake-cylinder spaces behind the pistons are supposed to be full of liquid, and excess slack has been taken up, forcing the piston 56 and diaphragm 51 apart and interposing liquid between them, which liquid is subject to the pressure exerted by the spring 22 of the smaller brake-cylinder piston 51.

In effecting an application of the brakes liquid under pressure enters the valve-casing 40 from the pipe 5^f and passes through the passage 47^b, controlled by the valve 47, into the pipe 5^g, and thence to the smaller brake-cylinder 6^a, forcing out the piston 51^b thereof, and thereby taking up the slack of the connections and bringing the brake-shoes against the wheels, as well as moving the axle-boxes up to their bearings in the pedestals. The pressure exerted by the liquid on the piston 51^b is transferred through the levers and connecting-rods to the brake-beams, and as the piston 56 and its push-rod 16 constitute the fulcrum or abutment at which the series of levers ends a force equal to that exerted by the liquid on the piston 51^b will be transferred to the piston 56 and by said piston, through the interposed liquid, to the diaphragm 51 and to the liquid on the right or outer side thereof. This pressure per square inch will be as the relative areas of the pistons 51 and 56.

When the liquid-pressure in the valve-casing 40 on the top of the piston 49 (from the pipe 5^f) plus the pressure on the top of the diaphragm 50 (from the larger brake-cylinder 6^a and pipe 5^h) exceeds the pressure of the spring 51^c on the diaphragm 50, the piston 49 is

moved down, allowing the valve 47 to be closed by the spring 48^a, and communication between the pipes 5^f and 5^g is thereby cut off and the liquid in both the small and large cylinders is locked therein. At this time the liquid-pressure in the pipe 5^f holds the check-valve 52 closed against the pressure on the inner side of the diaphragm 51 of the larger cylinder 6, said diaphragm having been theretofore subjected to such pressure from the piston of the smaller cylinder through the lever-and-link connections between the pistons 51^b and 56 and the body of liquid interposed between the piston 56 and the diaphragm 51. Liquid is therefore locked in both the cylinders 6 and 6^a.

Upon the further increase of pressure in the casing 40 sufficient to move the piston 49 against the increasing resistance of the spring 51^c with the decreased area of the piston 49, due to the seating of the valve 47, holding the valve 47^a, a further downward movement of the piston 49 is effected, thereby moving it away from the valve 47^a and admitting liquid under pressure from the pipe 5^f to the top of the diaphragm 50, which being of still larger area than the piston 49 overcomes the still increasing resistance of the spring 51^c and opens the portage under the valve 47^a to its full extent, thereby admitting fluid under pressure from the pipe 5^f through the pipe 5^h to the larger cylinder. Liquid then passes from the pipe 5^f through the passage 49^a, port 49^b, and pipe 5^h into the cylinder 6, moving the diaphragm 51 thereof outwardly or to the left, said diaphragm, through the liquid interposed between it and the piston 56, also moving the piston 56 in the same direction. As soon as the liquid-pressure passes into the larger cylinder the direction of pressure is reversed and the piston of the smaller cylinder becomes the fulcrum, the pressure per square inch in the smaller cylinder rising in proportion to the relative transverse areas of the cylinders and holding the valve 47 firmly to its seat. This movement of the diaphragm 51 and piston 56 applies the brakes with the desired degree of force, and the pressure reacts through the brake-levers and connections, the pin 14^a acting as a fulcrum, and proportionately raises the pressure in the smaller cylinder 6^a.

Upon the release of pressure in the pipe 5^f for the purpose of releasing the brakes the pressure in the larger brake-cylinder 6 unseats the release check-valve 52, as shown in Fig. 4, and the pressure on the right-hand side of the diaphragm 51 thereby falls below that at which the movable members of the controlling-valve mechanism are held in the positions shown in Fig. 3, relieving the pressure on the top of the piston 49 and diaphragm 50, which thereupon move upwardly until the valve 47^a is seated by the contact of the piston 49 therewith, as shown in Fig. 4. The pressure in the larger brake-cylinder

6 and on the top of the piston 49 and diaphragm 50 decreases as the liquid is discharged from the space on the right-hand side of the diaphragm 51 by the combined action 5 of the spring 59 and the pressure in the smaller brake-cylinder 6^a acting through the levers on the piston 56 and the liquid interposed between said piston and the diaphragm 51. Said diaphragm 51 is brought to the position shown in Fig. 1 and again becomes the fulcrum or abutment for the piston of the smaller cylinder, relieving the pressure in the smaller cylinder and on the top of the valve 47. The pressure on the top of the valve 47 being less than the tension of the controlling-valve spring 51^c, said spring further raises the piston 49 of the controlling-valve mechanism and unseats the valve 47, and liquid from the smaller cylinder passes 20 through the pipe 5^e and passage 47^b to the pipe 5^f, leaving the parts in the positions shown in Fig. 1.

Liquid which may leak past the pistons 56 and 51^b is discharged to the pipe 5^f through 25 the release-pipes 60^b and 60^a, controlled by a release-cock 60^a, when said cock is in the position shown in Fig. 1, and liquid may be discharged from the space between the piston 56 and diaphragm 51 as desired through 30 the pipe 60^a by turning the release-cock a quarter of a revolution from the position shown. The construction of my present invention accords substantially in these particulars with that of my Letters Patent No. 35 641,625, aforesaid.

The improved controlling-valve mechanism which is herein set forth presents in practice the substantial advantage of enabling communication between the pipe 5^f and the 40 smaller cylinder to be positively and effectively closed before communication is opened from the pipe 5^f to the larger cylinder, so that liquid may be locked with certainty in the smaller cylinder to enable its piston to act as 45 an abutment for that of the larger cylinder. The employment of the diaphragm 50 in combination with the two superposed lift-valves completely prevents leakage and loss of liquid, and the entire construction is more easily 50 constructed and maintained and more certain in its operation than those of the prior patents referred to.

I claim as my invention and desire to secure by Letters Patent—

1. In a mechanism for applying hydraulic 55 pressure, the combination, substantially as set forth, of two cylinders, of different areas of transverse sections, pistons fitted therein, two movable pressure members, connections coupling the pistons one to the other and to 60 the pressure members, a pipe for the supply and release of liquid under pressure, a valve-casing communicating therewith, a piston fitting therein and having an internal passage communicating with the larger cylinder, a 65 diaphragm secured peripherally in the casing and connected to said piston, a spring bearing on said diaphragm, a valve controlling communication between the liquid supply and release pipe and the smaller cylinder, a 70 valve of smaller diameter connected thereto and adapted to control the internal passage of the piston, and a release check-valve controlling communication between the larger cylinder and the liquid supply and release 75 pipe.

2. In a brake apparatus, the combination, substantially as set forth, of a larger and a smaller brake-cylinder connected by an interposed cylinder-head, pistons fitted in said cylinder, connections coupling said pistons one to the other and to brake-operating levers, a flexible diaphragm and a perforated stop-plate, each fixed peripherally to the larger cylinder adjacent to the interposed 80 cylinder-head, a liquid supply and release pipe, pipes leading therefrom to the smaller cylinder and to the space between the flexible diaphragm and the adjacent cylinder-head, a valvular mechanism, actuated by oppositely-exerted liquid and spring pressures, 85 through which valvular mechanism and passages controlled thereby liquid under pressure is delivered to the smaller cylinder and to the space between the diaphragm of the 90 larger cylinder and the adjacent cylinder-head, and a release check-valve controlling communication between said space and the 95 liquid supply and release pipe.

FRANCIS L. CLARK.
